UNITED STATES PATENT OFFICE.

ABRAHAM WEXELMAN, OF BROOKLYN, NEW YORK.

KNOCKDOWN TABLE.

Application filed August 24, 1926. Serial No. 131,178.

This invention relates to tables and more particularly to kitchen tables that are of knock-down construction.

One of the objects of the invention is 5 to provide a table that is easily and quickly assembled or disassembled for moving or transportation.

A further object is in the provision of connecting means whereby the table may 10 be made of wood or metal.

These and other objects are accomplished by the novel construction, combination and arrangement of parts, hereinafter described and illustrated in the accompanying drawing, forming a material part of this disclosure, and in which:—

Figure 1 is a partial sectional, partial front elevational view of a table constructed in accordance with the preferred form of 20 this invention.

Figure 2 is a fragmentary bottom plan view thereof.

Figure 3 is a perspective view of the connection element, drawn to an increased scale.

Figure 4 is a view similar to Figure 2 showing a modification of the same.

Figure 5 is a fragmentary partial sectional view taken at right angles to Figure 4.

In the drawing, the numeral 10 generally 30 designates the wooden legs of a table to which is secured on the inner sides a pair of flattened tube brackets 11 having a slot 12 through one side extending nearly along its entire length and openings 13 in the 35 opposite side by which the element is fastened to the legs.

Engageable in the slot 12 to seat on the bottom thereof is a U-shaped keeper 14 secured through openings 15 to side pieces 16, 40 rear elements 17 and front members 18, the front and rear members carrying angled guides 19 on which is slidable a plurality of drawers 20.

Passing through the side pieces, at suitable 45 locations are bolts 21 engageable with wing

nuts 22, the heads 23 of the bolts being countersunk in a cross-piece 24 flush with the front and rear elements 18 and 17 respectively and on which a metal table top 25 may be secured by screws 26 passing therethrough.

Thus it may be seen that the table is of knock-down construction and is easily taken apart or reassembled by merely raising the top 25 and disengaging the keepers 14 from the brackets 11.

In Figures 4 and 5, a metal table top 30 is secured by screws 31 to a wooden-cross-piece 32.

Fixed by bolts 34 to the cross-piece 32 is 60 a metal channel-shaped member 33 having at its ends substantially at right angles thereto, an element 35 bent partially back on itself at 36 to engage in slots 37 formed vertically in the inner sides of hollow metal 65 legs 38, the front piece 39 also of channel cross section having similar elements 35'.

Thus it may be seen that a substantially all-metal table has been disclosed that is of knock-down construction and which is quickly and easily operated.

From the foregoing, it is obvious that a simple device for the purposes intended has been described and it is to be understood that it is not intended that this be interpreted as limitative, as changes in construction may be made without departing from the scope of the appended claim.

Having thus described my invention, what I claim as new and desire to secure by 80 Letters Patent, is:—

A demountable table comprising a plurality of legs, partially slotted flattened tube brackets secured to said legs, U-shaped keepers fixed to the side, front and rear members 85 of the table and means in the side pieces to firmly secure the table top thereon.

In witness whereof I have affixed my signature.

ABRAHAM WEXELMAN.
